MOBILE ADVERTISING SIGN

Roy J. Ford and Bobby R. Ford, both of
P.O. Box 127, Fort Worth, Tex.

Filed Aug. 16, 1965, Ser. No. 86,582

Term of patent 14 years

(Cl. D1—12)

The figure is a perspective view taken from the front and one side of a mobile advertising sign showing our new design. The rear and opposite side are essentially the same as the front and side shown.

The dominant features of our design reside in the portions shown in full lines.

We claim:

The ornamental design for a mobile advertising sign, as shown and described.
